UNITED STATES PATENT OFFICE.

CHARLES G. FLICK, OF TORONTO, ONTARIO, CANADA.

GLASS-POLISHER.

SPECIFICATION forming part of Letters Patent No. 423,749, dated March 18, 1890.

Application filed July 8, 1889. Serial No. 316,779. (No model.)

To all whom it may concern:

Be it known that I, CHARLES G. FLICK, glass-beveler, of the city of Toronto, in the county of York, in the Province of Ontario, Canada, 5 have invented a certain new and useful Improvement in Glass-Polishers, of which the following is a specification.

The object of the invention is to design a device by which pumice-stone mixed in water 10 may be regularly and properly applied to the surface of the polishing-wheel; and it consists, essentially, of a tank to contain the mixed pumice-stone and having a revolving mixer and a device by which the pumice-stone 15 is permitted to escape intermittently into a channel, by which it is conveyed to a sponge pressed against the surface of the polishing-wheel, the whole being constructed in detail, substantially as hereinafter more particularly 20 explained.

Figure 1 is a perspective view of my device. Fig. 2 is a detail of the sponge Q and block P.

A represents an ordinary polishing-wheel, 25 such as is commonly used for the purpose of polishing the beveled edge of a glass-plate. This wheel is suitably journaled in the frame B, and its lower portion is inclosed by a box C. This box I leave without a bottom, but 30 provide a slanting spout D, onto which the surplus pumice falls and is conducted to the pail E.

F is a tank suitably supported, as indicated, above the wheel A.

35 G is a mixer suitably journaled within the tank F and caused to revolve by the gearing H. A hole I is made in the bottom of the tank F, and a spindle J is inserted in the said hole. The head of this spindle effectually 40 stops the hole and prevents the pumice escaping when the spindle is supported by its head, as indicated in the drawings. A spindle K is supported, as indicated, and derives motion from the gearing H. On the outer 45 end of this spindle K a crank L is placed, which crank is suitably connected to the sliding bar M, as shown. On the end of this sliding bar I fix an arm N, which extends below the bottom end of the spindle J. When

50 the gearing H is put in motion for the purpose of operating the mixer G, the bar M derives a reciprocating motion, causing the arm

N to come in contact with and raise the spindle J every revolution of the spindle K. By thus raising the spindle J so that its head 55 shall be clear of the bottom of the tank a given quantity of the pumice is permitted to escape and fall onto the slanting spout O, which conveys it to the wheel A, as indicated. Immediately below the spout O a block P is 60 fixed, and a sponge Q is attached to the block P and held by the said block against the surface of the wheel A in such a manner that the pumice falling from the spout O onto the sponge Q is applied to the surface of the 65 wheel A. The surplus pumice falls onto the slanting spout D and is conveyed into the pail E.

From this description it will be seen that a regular supply of pumice is applied to the 70 surface of the wheel A, and it will be observed that whenever it becomes necessary to turn up the surface of the wheel A the pail E and spout D may be removed, when the shavings will simply fall through the box C and will 75 not mix or interfere with the pumice.

As it is sometimes necessary to operate the mixer without opening the hole I, I fix the arm N in such a manner that it may be easily turned clear of the end of the spindle J, in 80 which case the mixing mechanism may operate without opening the hole I, or, in other words, without permitting the pumice to escape from the tank.

What I claim as my invention is—

1. A tank F, provided with a revolving mixer G and having a hole I in its bottom stopped by the vertically-adjustable spindle J, in combination with the spindle K, crank L, sliding bar M, and arm N, arranged substantially as and for the purpose specified.

2. A tank F, provided with a revolving mixer G and having a hole I in its bottom stopped by the vertically-adjustable spindle J, in combination with the spindle K, crank 95 L, sliding bar M, arm N, slanting spout O, and sponge Q, substantially as and for the purpose specified.

Toronto, June 17, 1889.

CHAS. G. FLICK.

In presence of—

CHARLES C. BALDWIN,
W. G. MCMILLAN.
